UNITED STATES PATENT OFFICE.

MARTIN R. SCHAFFER, OF READING, PENNSYLVANIA.

DOOR-BELL AND BURGLAR-ALARM.

1,130,436.

Specification of Letters Patent.

Patented Mar. 2, 1915.

Application filed March 13, 1914. Serial No. 824,423.

To all whom it may concern:

Be it known that I, MARTIN R. SCHAFFER, a citizen of the United States, residing at Reading, in the county of Berks and State of Pennsylvania, have invented certain new and useful Improvements in Door-Bells and Burglar-Alarms, of which the following is a specification.

My invention relates to improvements in 10 combined door bell and burglar alarm, and the main object of my invention is the provision of means which will serve the two-fold purpose of a door bell or burglar alarm, and which will be of such simple and inexpensive construction as to make its use 15 highly desirable.

Another object of my invention is the provision of means which can be operated from the door knob or by means of a push-button 20 to serve the purpose of a door bell or burglar alarm, which will be absolutely positive and reliable in operation, which will be of compact and small size, which will be of ornamental and attractive appearance, and 25 from every point of view will be thoroughly efficient and practical.

With these objects in view, my invention consists of a combined door-bell and burglar alarm embodying novel features of construction and combination of parts, substantially as disclosed herein.

In order that the construction in detail and the operation of my invention may be fully understood and its many advantages 35 be appreciated, I have illustrated in the accompanying drawing a mechanism embodying my invention.

Figure 1 represents a front elevation or face view of my invention, partly broken 40 away to illustrate the construction of certain parts of the mechanism. Fig. 2 represents a vertical central sectional view, partly in elevation, of my improvement applied to a door, and Fig. 3 represents a view, 45 partly in section and partly in elevation, of a push button mechanism for use in connection with my improvement.

In the drawings: The letter A designates a portion of the door to which is attached 50 by means of screws or like fastenings B, the base or supporting plate C, which is spaced or raised away from the door and has fulcrumed thereon at D, the lever E, whose upper end is formed with the open head or 55 yoke F, having its upper wall formed with teeth to provide a rack G, and its lower end

provided with a vertical slot H, adapted to receive the stem J, on the head J', fitted in said opening or slot H, and with said pin and lever is connected the strap K, having 60 near its lower end an angular opening K', to fit upon the spindle L, of the door knob L'. From this construction it will be observed that to the door is connected the base or supporting plate and pivoted thereon is 65 the lever E, and that the turning of the door knob L', rocks the strap K, which rocking is transmitted to the lower slotted end of the lever E, moving said lever upon the supporting plate and in consequence reciprocating 70 the yoke F, with its rack G, which rack meshes with the pinion M, mounted on the pin or stud N, which supports and secures the bell O, turns the wheel P, formed with the series of teeth Q, and that the rotation 75 of said toothed wheel brings its teeth into contact with the arm R, carrying the hammer R', and formed with an attaching portion R², and a pair of spring loops or bends R³, the engagement of the teeth with said 80 spring arm causing the hammer to strike the bell with a quick movement sounding the alarm or ringing the bell as a door bell.

The construction described is operated by means of the door knob, and if desired, the 85 push button shown in Fig. 3 may be employed, which consists of the hollow guide casing S, secured in the door, the push button S', formed with the stem S², having the inclined lug S³, adapted to enter the key slot 90 C' of the supporting plate and engage the lower portion of the lever at one side, which action moves the lever in the same manner as the turning of the door knob, and in a like way rings the bell, and to restore the 95 push-button to normal position, I place around its stem S², the coiled spring S⁴, which returns the push button to normal or initial position. Also for the purpose of returning the lever to normal position or to 100 assist in this function, I employ the coiled spring T, whose ends T' are connected to the supporting plate and the lever, as shown in Fig. 1, said spring assisting in restoring the lever to normal position.

From the foregoing description, taken in connection with the drawing, the operation of my improvement will be readily understood, and it will be apparent that the reciprocation of the lever, either by the turning of the knob or the pushing inward of the push-button, causes the rack on said 105 110

lever to rotate the meshing pinion, which revolves the toothed wheel, causing its teeth to quickly engage the spring hammer arm, bringing its hammer rapidly against the bell, producing a loud vibrating alarm, which will prove efficient either for service as a door-bell or burglar-alarm.

I claim:

10 A supporting base, a lever mounted thereon and having at one end a yoke with teeth and at the other end an elongated slot, a strap having one end provided with an angular opening to fit upon the spindle of a door knob, a stem carried by the other end 15 of said strap and engageable in the slot of

the lever, a stud carried by the base, a pinion loosely mounted on said stud and engaging the teeth of said yoke, a toothed wheel loosely mounted on said stud and connected to said pinion, a bell and a hammer mounted on said stud, said hammer having spring bends and a portion in the path of said toothed wheel, said strap adapted to be rocked by turning of the door knob. 20

In testimony whereof I affix my signature 25 in presence of two witnesses.

MARTIN R. SCHAFFER.

Witnesses:

JOHN L. TREXLER,
M. A. SCHAFFER.
